US00D450839B1

(12) **United States Design Patent** (10) Patent No.: **US D450,839 S**
Junker (45) Date of Patent: **** Nov. 20, 2001**

(54) **HANDLE FOR INTRODUCER SHEATH**

6,083,207 * 7/2000 Heck 604/164

(76) Inventor: **Larry G. Junker**, 8930 Roam La. East,
Inverness, FL (US) 34450

FOREIGN PATENT DOCUMENTS

3834600 6/1992 (DE) .

(**) Term: **14 Years**

* cited by examiner

(21) Appl. No.: **29/118,289***Primary Examiner*—Ian Simmons(22) Filed: **Feb. 7, 2000**

(74) Attorney, Agent, or Firm—Frijouf, Rust & Pyle P.A.

(51) **LOC (7) Cl.** ..... **24-02****CLAIM**(52) **U.S. Cl.** ..... **D24/130**The ornamental design for a handle for introducer sheath, as
shown and described.(58) **Field of Search** D24/112, 130,
D24/133; 604/164.01, 164.05, 165.3, 167,
160, 161, 523, 264**DESCRIPTION**(56) **References Cited**FIG. 1 is a perspective view of my new design for a handle
for introducer sheath with the sheath being shown in phan-
tom;

U.S. PATENT DOCUMENTS

FIG. 2 is a perspective view thereof, shown in severed
condition;

DE 3834600 C1 6/1992

Primary Examiner—Eric L Goodman

**EX PARTE
REEXAMINATION CERTIFICATE
ISSUED UNDER 35 U.S.C. 307**

AS A RESULT OF REEXAMINATION, IT HAS BEEN
DETERMINED THAT:

The patentability of the single design claim is confirmed.

The ornamental design for a handle for introducer sheath,
as shown and described.
